EP 0359687 A2 * 3/1990 ..... A63B 47/02

Primary Examiner — Catherine A Tuttle(74) *Attorney, Agent, or Firm* — Dunlap Bennett & Ludwig PLLC(57) **CLAIM**

The ornamental design for a bocce ball retriever, as shown and described.

DESCRIPTION

FIG. 1 is a top front perspective view of a bocce ball retriever, embodying my new design;

FIG. 2 is a front elevation view thereof;

FIG. 3 is a rear elevation view thereof;

FIG. 4 is a right elevation view thereof, the left elevation view being a mirror image of FIG. 4;

FIG. 5 is a top plan view thereof; and,

FIG. 6 is a bottom plan view thereof.

The broken lines shown in the drawings depict portions of the bocce ball retriever that form no part of the claimed design.
